UNITED STATES PATENT OFFICE.

ARTHUR KNOX, OF ALPENA, SOUTH DAKOTA.

APPARATUS FOR COOLING CYLINDERS OF GAS-ENGINES.

No. 888,909.

Specification of Letters Patent.

Patented May 26, 1908.

Application filed September 11, 1906. Serial No. 334,162.

To all whom it may concern:

Be it known that I, ARTHUR KNOX, a citizen of the United States, residing at Alpena, in the county of Jerauld and State of South Dakota, have invented certain new and useful Improvements in Apparatus for Cooling Cylinders of Gas-Engines; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in cooling apparatus for engines, and comprises series of disks which are adapted to be mounted to rotate with a tank 20 and in the water of circulation about a cylinder of an engine, thereby causing the water as it circulates through the tank to present a large area of cooling surface.

The invention comprises various details of 25 construction and combinations and arrangements of parts which will be hereinafter fully described and then specifically defined in the appended claims.

I illustrate my invention in the accompanying drawings, in which:

Figure 1 is a vertical section through a cylinder, illustrating my invention; and Fig. 2 is a top plan view.

Reference now being had to the details of 35 the drawings by letter, A designates the cylinder of an engine about which a water jacket B is formed, through which water is caused to circulate in any suitable manner.

C designates a driving wheel which is 40 mounted upon gas engine crank shaft D, and D' designates a crank arm to said shaft and to which one end of pitman rod E is pivotally attached, the other end of said rod being pivoted to the piston of the engine.

F designates a tank which is open at its 45 top and has an exhaust pipe G leading into the exit passageway H. Said exhaust pipe G leads from one end of the cylinder to said exhaust passage. N designates a shaft 50 mounted in suitable bearings, and O, O designate a series of disks which are fixed to the shaft N and adapted to be rotated within said tank F. A band wheel Q is fixed to the end of the shaft N, and a second band wheel

Q' is fixed to rotate with the shaft D. A 55 band R travels about said band wheels and is adapted to impart a rotary movement to the shaft N with which said disks rotate.

The operation of my apparatus is simple and is as follows: As the water circulates 60 about the engine in any suitable manner and flows through the tank F, the rotary movement of the disk is caused to bring the water about the opposite faces of the disk, thus serving to cool the same, while air is drawn 65 into the tank by the suction caused by the exhaust and coming in contact with the water will further cause the same to cool. After the water has been cooled by means of the disks, it continues on its circulating 70 course about the cylinder.

From the foregoing, it will be noted that by the provision of the apparatus shown and described, a simple and efficient means is afforded for causing the water which circulates 75 about the cylinder to be brought into contact with large radiating surfaces, thus taking up the heat which is absorbed from the cylinder and causing the same to be carried off by the draft of air which is drawn 80 through the tank by the action of the exhaust, thereby keeping the water at a comparatively low temperature.

What I claim is:

A water cooling apparatus for engines 85 comprising a cylinder having a continuous water jacket about one end and the circumference thereof and having a duct leading from the interior of the cylinder through the water jacket, a tank having openings at positions diametrically opposite at the bottom thereof, pipes leading from said openings and communicating with the interior of the water jacket at points diametrically opposite, said tank having a flue leading from its upper 95 portion, the side wall of which is apertured, a pipe leading through the aperture in said flue and through said duct from the interior of the cylinder through the water jacket, a shaft journaled in said tank, a series of disks 100 spaced apart and fixed to said shaft, and means for rotating the shaft, as set forth.

In testimony whereof I hereunto affix my signature in the presence of two witnesses.

ARTHUR KNOX.
